(57) **CLAIM**

The ornamental design for a Bluetooth headset, as shown and described.

DESCRIPTION

FIG. 1 is a front elevational view of a Bluetooth headset showing my new design shown separately from the case to show aspects of the design that are not visible when combined;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a front elevational view of the case shown separately to show aspects of the design that are not visible when combined;

FIG. 9 is a rear elevational view thereof;

FIG. 10 is a left side view thereof;

FIG. 11 is a right side view thereof;

FIG. 12 is a top plan view thereof;

FIG. 13 is a bottom plan view thereof;

FIG. 14 is a perspective view thereof; and,

FIG. 15 is a perspective view of the Bluetooth headset and the case combined.

The broken lines in the drawings depict portions of the Bluetooth headset that form no part of the claimed design.

1 Claim, 15 Drawing Sheets
